UNITED STATES PATENT OFFICE

136,819

DESIGN FOR A VEHICLE

Delmar G. Roos, Toledo, Ohio, assignor to Willys-
Overland Motors, Inc., Toledo, Ohio, a corpora-
tion of Delaware

Application December 26, 1942, Serial No. 109,146

Term of patent 3½ years

To all whom it may concern:

Be it known that I, Delmar G. Roos, a citizen of the United States, residing at 2234 Meadowood Road, Toledo, county of Lucas, and State of Ohio, have invented a new, original, and ornamental Design for Vehicles, of which the following is a specification, reference being had to the accompanying drawings, forming part thereof.

In the drawings,

Figure 1 is a side elevational view of a vehicle showing my new design.

Figure 2 is a plan view of the vehicle shown in Figure 1.

Figure 3 is a front elevational view of the vehicle shown in Figure 1.

Figure 4 is a rear elevational view of the vehicle shown in Figure 1.

Figure 5 is a top perspective view of the body portion shown in full lines in Figures 1, 2 and 3.

The dominant features of my vehicle design are shown in solid black lines in the drawings.

I claim:

The ornamental design for a vehicle, substantially as shown and described.

DELMAR G. ROOS.
